FIG. 2.

UNITED STATES PATENT OFFICE.

GEORGE N. SIMPSON AND ARTHUR M. SIMPSON, OF CHICAGO, ILLINOIS.

CAR CONTROL.

1,349,388.

Specification of Letters Patent. Patented Aug. 10, 1920.

Application filed August 29, 1919. Serial No. 320,725.

To all whom it may concern:

Be it known that we, GEORGE N. SIMPSON and ARTHUR M. SIMPSON, citizens of the United States, residing at Chicago, in the 5 county of Cook and State of Illinois, have invented new and useful Improvements in Car Controls, of which the following is a specification.

This invention relates to improvements 10 in apparatus for controlling the progress of cars on a railway track; and is more especially adapted for use in connection with mine cars. In the unloading of mine cars it is customary to feed the loaded cars to 15 the unloading mechanism by allowing them to run down an inclined track or propelling them in trains or trips. Since the unloading process requires a certain amount of time for each car or group of cars, it is 20 necessary that a predetermined number of cars at a time be permitted to enter the unloading apparatus while the remaining cars on the inclined track are held back.

It is obvious that in operation such devices 25 are exposed to rough usage and severe impacts and jars. This is apparent when it is borne in mind that they are adapted to engage with moving cars in trains or trips, at times heavily loaded and moving with 30 considerable velocity down a rather steep grade. Such devices must be strong enough to stop the movement of such cars when raised to operative position without damage to any of the parts.

35 There have been made heretofore various forms of tread blocks, stops, and horns, adapted to be moved into operative position to engage the wheel or some other part of a moving car, and lowered into inoperative position; with various constructions and various means of controlling the same.

Most devices heretofore made have been 40 objectionable for the reason that they could not be heavily and strongly enough made to withstand the severe uses to which exposed 45 without making the parts so heavy and cumbersome as to prevent facile operation. Most devices heretofore made have also been objectionable on account of the large amount 50 of space required for their installation. The use of such car controls is frequently required within mines at the bottom of the shaft where space is limited. In such places the depth of excavation below the track required 55 for the installation of the car control is of primary importance since, as stated be-

fore, space must be conserved in every instance, and the difficulty of making an excavation and keeping the same free from water, coal, refuse, and dirt, is great.

We have invented a car control which is 60 free from objections to the devices heretofore used as pointed out above. Our improved car control can be easily and cheaply made, and is compact, strong, and durable, 65 and is so designed that it can be readily operated with a minimum of effort. The control is also so designed that it may be installed in a track, requiring a minimum amount of space, with a very shallow ex- 70

cavation below the level of the rails. As here shown, our invention comprises a tread block or stop adapted to be placed in the rail of the track, and so designed that it can be raised to lie in the path of the 75 wheels of the cars thus forming a stop, or lowered into inoperative position allowing the car wheels to pass freely over it. When the stop is in its raised position, it presents an inclined surface from the rail level to the 80 approaching car wheel so that the wheel will ascend it a short distance thus making use of the weight of the car to check the speed and preventing an abrupt stop. This is one of the features of our invention, since 85 most of the stops heretofore made engage with the wheel or other part of the car at a point some distance above the rail causing an abrupt stop with little or no resiliency.

A device embodying the feature of our 90 invention is shown in the accompanying drawings in which: Figure 1 is a top plan view of a section of railway track with our improved car control in place. Fig. 2 is a similar view in side elevation. Fig. 3 is a 95 similar view in end elevation. Fig. 4 is a diagrammatic view showing the stop lowered, or in its inoperative position.

As shown in said drawings 1 and 2 indicate angle irons arranged to form one rail 100 of a railway track, the angle irons 5 and 6 constituting the other. As shown in said drawings, the angle irons 1 and 2 are arranged with two of their surfaces extending outwardly and horizontally to form the 105 base of a rail, the other two surfaces being separated a short distance and extending upwardly, so that a car wheel can run on their upper edges. The angle irons 5 and 6 are similarly arranged. In general, the 110 effect of such an arrangement of angle irons is to form two parallel rails, each with a

longitudinal slot extending throughout its entire length. The angle irons 1, 2, 5, and 6 are firmly mounted or set in place in any convenient manner, and, as here shown, they are supported by the cross members 8, 8. A pair of car wheels on a car are indicated by 10, the arrow indicating the course of travel.

Pivoted between the angle irons 5 and 6 by means of the pivot 13 is the tread block or stop 15 which is adapted to be raised to the position shown in Fig. 2 to lie in the path of the car wheel 10, presenting an inclined surface to act as a stop for each wheel, or lowered down between the angle irons 5 and 6 to the inoperative position, as shown diagrammatically in Fig. 4. Directly opposite the stop 15 is a similar stop arranged between the angle irons 1 and 2, but since the construction and operation of the two stops is the same we will describe but one. The bottom surface of the stop 15 at about its middle part is concaved as indicated at 17. Lying below the stop 15 and so arranged that the stop 15 when in its lowered position may rest upon it, (see Fig. 4) is a roller 19 rotatively mounted on the transverse shaft 20. The shaft 20 extends across to a position below the angle irons 1 and 2 and there supports a similar roller under the other stop which is not shown. Each end of the shaft 20 is supported in a bearing block 22 which in turn is supported by a firm foundation indicated by 24. As here shown the foundation 24 consists of a heavy channel iron bolted at 25, 25, to the channel irons 26, 26 which in turn are supported by the angle irons 5 and 6 by means of the bolts 27, 27.

40 A short distance from the stop 15, there is pivotally mounted between the angle irons 5 and 6 a bell crank 28 on the pivot 29. The arm of such bell crank 28 lying toward the stop 15 has pivotally attached to its end the connecting rod 31 the end of which carries rotatively mounted on it the roller 33 which is slightly smaller in size than the roller 19.

The bell crank 28 is of such size, and the connecting rod 31 is of such length, and these parts are so mounted by means of the pivot 29 that movement of the bell crank 28 on such pivot 29 will operate to move the roller 33 from the position shown diagrammatically in Fig. 4 up over the roller 19, between such roller and the stop 15, raising such stop 15 to the position shown in Fig. 2. The limit of movement of the roller 33 is reached when the connecting rod 31 and the attached arm of the bell crank 28 are in line. When in this position the roller 33 is directly above the roller 19, and the stop 15 is in its raised position as shown in Fig. 2. The limit of movement of the roller 33 in the opposite direction is shown diagram-

matically in Fig. 4. When in this position the roller 33 is no longer in contact with the stop 15 and such stop rests directly on the roller 19.

It will be noted, that in the operation of the device, the raising of the stop 15 is accomplished with no friction at all other than that at the respective pivots. The bottom surface of the end of the stop 15 is curved as indicated by 57, so that the roller 75 33 as it forces the stop 15 to its raised position will roll along such curved surface 57, the roller 19 which supports the roller 33 being free to rotate to permit such required rotation of the roller 33. As here shown the 80 curvature at 57 is designed to permit a fast upward movement of the stop 15 at first as the roller 33 is forced under the stop, such movement becoming slower as the stop 15 approaches the limit of its upward movement. It is evident that from this construction a slight amount of power exerted on the bell crank 28 will operate the stop 15 against considerable resistance.

Although we have shown a specific curvature at 57 and certain sizes for the rollers 33 and 19 and a specific means for moving the roller 33, it is evident, that without detracting from the spirit of this invention, the sizes and arrangement and degrees of 95 curvature of the various parts, and the means of operating the same, may be varied.

It will be noted that when the stop 15 is in its raised position as shown in Fig. 2 with the roller 33 lying directly above the roller 19, pressure of the car wheel 10 on the stop 15 will exert downward pressure on the rollers 33 and 19 but will have no tendency whatsoever to force the roller 33 out from under the stop 15. It is apparent therefore 10 that when the stop is in its raised position no effort is required to maintain it in such position. This is one of the features of our invention since most of the stops heretofore used have required considerable effort to retain them in operative position.

It is evident that various means may be used for operating the bell crank 28 and the corresponding bell crank between the angle irons 1 and 2. For the purpose merely of 1 showing a single means of operating these bell cranks we have shown in this specification two bell cranks 61, 61 mounted on vertical pivots below the angle irons 1 and 2, and, 5 and 6. Each of the bell cranks 61, 1 61 has one of its arms joined by the connecting rod 62 to one of the arms of the bell crank 28. The other arms of the bell cranks 61, 61 are joined by the connecting bar 63. It is evident that transverse movement of 1 the bar 63 will operate through the bell cranks, 61, 61 to operate the bell cranks 28, 28 thus moving the rollers 33, 33 to operate the stops 15, 15 as above described. Such movement to the bar 63 may be imparted by 1

any desired means. We have here shown on the bar 63 a short projection 65 with a hole 67 to which may be attached a rod or bar leading to any form of operating mechanism.

5 Lying below the bar 63 we have shown a spiral spring 69 with one end attached to a stationary part 71 below the angle irons 5 and 6 and the other end connected by means 10 of the rod 73 to the bar 63 at 75. The spring 69 is so arranged that movement of the bar 63 to lower the stops 15, 15 will extend such spring, and release of the operating mechanism will permit such spring to draw the 15 bar 63 back into position as shown in Figs. 1 and 2, thus raising the stops 15, 15. It is evident, however, that without detracting from the spirit of this invention, the spring may be oppositely arranged so that it will 20 tend to keep the stops in their lowered position requiring power to raise them into operative position.

We claim:

1. In a car control, a stop adapted to be 25 moved to a position lying in the path of a car, and means for so moving said stop comprising a roller adapted to be forced against said stop.

2. In a car control, a stop with a curved surface adapted to be moved to a position 30 lying in the path of a car, and means for so moving said stop comprising a roller adapted to be forced against the curved surface of said stop.

3. In a car control, a stop adapted to be 35 moved to a position lying in the path of a car, and means for so moving said stop comprising a roller adapted to be forced between said stop and another roller.

4. In a car control, a stop adapted to be 40 moved from a position resting on a supporting roller, to a position lying in the path of a car, and means for so moving said stop comprising another roller adapted to be forced between the stop and the supporting 45 roller.

In witness whereof we have hereunto subscribed our names this 20 day of August 1919.

GEORGE N. SIMPSON.
ARTHUR M. SIMPSON.
